UNITED STATES PATENT OFFICE.

GUSTAV SCHULTZE, OF BERKELEY, CALIFORNIA.

DESIGN FOR A PUZZLE-BOARD.

SPECIFICATION forming part of Design No. 31,613, dated October 3, 1899.

Application filed June 7, 1899. Serial No. 719,741. Term of patent 31 years.

To all whom it may concern:

Be it known that I, GUSTAV SCHULTZE, a citizen of the United States, residing at Berkeley, in the county of Alameda, State of California, have invented and produced a new and original Design for a Puzzle-Board, of which the following is a specification, reference being had to the accompanying sheet of drawings, showing a part thereof.

10 Figure 1 is a plan view of the puzzle-board, showing my new design; and Fig. 2 is a cross-sectional view taken on line $x-x$ of Fig. 1.

15 As shown in the drawings, the leading or material feature of my design consists of the representation of a mutilated eight-pointed star outlined upon the bottom A of a box or receptacle C'. At six points of the star there is located a station B. In the drawings the stations B and B' are represented cylindrical 20 in shape, while the controlling-station D and

station D' are illustrated as diamond-shaped. The field or central portion C of the star designates the home station and point D the controlling-station. To one side of the controlling-station is located station D', in line with 25 station B'. Station D' designates what would be the eighth point of the star if the same were not a mutilated one.

Having thus described my invention, what I claim as new, and desire to secure protection in by design Letters Patent, is—

The design for a puzzle-board, as herein shown and described.

In testimony whereof I affix my signature, in the presence of witnesses, this 19th day of 35 May, 1899.

GUSTAV SCHULTZE.

In presence of—

N. A. ACKER,

WALTER F. VANE.
